UNITED STATES PATENT OFFICE.

WILHELM WOLF, OF REISHOLZ, NEAR DÜSSELDORF, GERMANY.

DISTRIBUTER FOR REFRIGERATORS.

No. 851,723.

Specification of Letters Patent.

Patented April 30, 1907.

Application filed December 4, 1906. Serial No. 346,311.

To all whom it may concern:

Be it known that I, WILHELM WOLF, a subject of the King of Prussia, residing at Reisholz, near Düsseldorf, in the Kingdom of Prussia, have invented certain new and useful Improvements in Distributers for Refrigerators, of which the following is a specification.

My present invention relates to a distributor for fluids (liquid or gas) in refrigerators, being principally used for distributing liquids in machines operating with ammonia.

In refrigerators the pipes in which the liquid circulates, in order to produce evaporation are subjected to different stresses, for which reason the efficiency of the refrigerator is unfavorably affected. Attempts have been made to obtain a uniform distribution by only charging the distributing pipes for a time. The apparatus heretofore used for this purpose have however the drawback that all the pipe ends or openings are controlled by a single valve or other opening or closing agent, so that, after the machine, is constructed, the conditions resulting are rendered permanent and the order in which the various pipes are opened cannot be subsequently altered. In such apparatus heretofore used it was also not possible to automatically regulate the entrance of the liquid into the pipes independent of the suction force of the temperature in the suction main of the compressor or in the vaporizer. According to my present invention the separate pipe openings of such a liquid controlling apparatus are opened in any desired manner and sequence, the valve or closing device for the pipe openings not being common to all the pipes, so that the latter are not directly dependent upon each other and can be opened independently. Further my invention consists in rendering the adjustment dependent upon the temperature or variations of pressure in the vaporizer or suction main of the compressor. In order to obtain this end with the ordinary means it is necessary to construct the driving mechanism for the closing devices of the pipes in such a manner that they can be easily moved in certain directions, these movements being utilized in effecting the regulation in the above sense.

In the accompanying drawing several forms of the liquid distributer are shown, Figure 1 being a longitudinal section of the arrangement with six pipes; Fig. 2 is a cross section, Fig. 3 is a similar section showing an

other form of the valve for closing the pipes. Fig. 4 is a detail plan view of a plate for attaching the pipes and Figs. 5, 6 and 7 show the manner of operation, and form, of the valve operating cams.

1 designates the casing of the distributer, into which the liquid or gas can be admitted through the cock 2. At the bottom of this casing the distributing pipes 8 are connected, 65 by any suitable means preferably by coupling plates *a*, Fig. 4, having a threaded aperture *a'* into which the pipe is screwed and lateral bolt-holes *a*² by means of which the plate may be screwed onto the casing. These 70 pipes are normally closed by the conical lift valves 6, which are provided with guiding extensions 4 which move in suitable bores in the top of the casing. The plugs 3 enable the valves to be removed and the springs 5 to 75 be inserted, by which latter the valves are normally pressed on their seats. In the casing 1 is provided a horizontal spindle 16 having lugs 7 in different relative positions. This spindle is rotated by the wheel 9 which 80 is driven in any desired manner from any rotating part of the distributer, so that the cams 7 are moved under the guides 4 one after the other and the valves thus raised. The liquid enters in corresponding order into 85 the pipes 8.

In Fig. 3 another form of the valve is shown. Instead of the conical lift valves 6 plate springs 15 are used to close the pipes 8. One end of each of these springs covers the 90 end of a pipe while the other end of said spring is attached to the casing. These plate springs are also operated by cams arranged under the same. Fig. 1 also shows how the stroke or time of opening of the separate 95 valves can be altered according to the temperature or variations of pressure in the vaporizer or suction main of the compressor.

13 designates the suction main by way of example, in which a regulator 10 is provided. Said regulator has a piston 11 which can move up and down in the cylinder. If the pressure in the suction main decreases the piston is raised by a spring while on the pressure increasing the piston is moved down and 105 the spring is compressed. This movement of the piston is transferred by the lever 14 provided with a forked arm to the spindle 16, so that the latter is moved to the right when the pressure in the suction main sinks and 110 the piston rises and to the left when the pressure in the suction main is increased. The

effect of this horizontal movement of the spindle 16 on the stroke of the valves is evident from Figs. 5, 6 and 7. Figs. 5 and 6 show how the cams 7 engages with the circular bottom of the cylinder 4. If the cam is moved laterally, as shown in Fig. 6, it remains in contact with the circular bottom for a shorter time. The valve will accordingly be raised to a smaller extent and will close sooner. This operation of the cams may be assisted by suitably shaping their ends. Fig. 7 shows a form of cam which is particularly suitable for the form of valve shown in Fig. 3. The cam is beveled off so that when said cam is moved longitudinally the same regulation is obtained with regard to its action on the springs 15 as above explained in regard to Figs. 5 and 6. In Fig. 1 is shown how weights 12 may be adopted to differently load the piston 11 so that a very wide range of regulation is afforded.

The new device can of course be modified in various ways. Under some circumstances it may be preferable to use another form of valve. Two or more valves may if desired be united to a group and raised together, the essential feature being that the separate valves or the like of groups of valves or the like are, and can be moved independent of each other. Further the manner of regulating the operation of the valves according to the temperature or variation of pressure in the vaporizer or suction main can be carried out by other means than those shown in the drawing, although a piston subject to the pressure of the gas may be regarded as the most practical means for the purpose. Instead of the rods etc, used to transfer the motion of the piston 11 to the spindle 16 any other suitable means may be adopted.

What I claim and desire to secure by Letters Patent of the United States is:—

1. In a device of the character described, the combination with a plurality of distributing pipes, means to close the latter, means to operate the closing means independently of each other, and means to change the normal relation between the closing means and the means to operate the latter.

2. In a device of the character described, the combination with a plurality of distributing pipes, means to normally close the latter, means to operate the closing means independently of each other and means to automatically change the normal relation between the closing means and the means to operate the latter.

3. In a device of the character described, the combination with a plurality of distributing pipes, valves normally closing the latter, means to open said valves independently of each other, a suction main, and mechanism operated by the variation of pressure therein to change the normal relation between the valves and their opening means.

4. In a device of the character described, the combination of a plurality of distributing pipes, valves normally closing the latter, a plurality of operating members for said valves, in different positions relative to the latter and means to change the normal relation between the valves and the operating members.

5. In a device of the character described, the combination of a plurality of distributing pipes, valves normally closing the latter, an operating member for each valve, means to control the operating members, and means to shift the controlling means.

6. In a device of the character described, the combination of a plurality of distributing pipes, valves normally closing the latter, an operating member for each valve, means to control the operating members, and means to automatically shift the controlling means.

7. In a device of the character described, the combination of a plurality of distributing pipes, valves normally closing the latter, an operating member for each valve, means to control the operating members, and pressure operated mechanism adapted to change the normal relation between the valves and the operating members.

8. In a device of the character described, the combination of a plurality of distributing pipes, valves normally closing the latter, a spindle proximate to the valves, cams on the spindle in different relative positions and means to move the spindle longitudinally for the purpose specified.

9. In a device of the character described, the combination of a plurality of distributing pipes, valves normally closing the latter, a spindle proximate to the valves, cams on the spindle in different relative positions and pressure operated mechanism to move the spindle longitudinally for the purpose specified.

10. In a device of the character described, the combination of a plurality of distributing pipes, valves normally closing the latter, a spindle proximate the valves, means to rotate the spindle, cams on the spindle adapted to open the valves in sequence, pressure operated mechanism to move the spindle longitudinally, and means to adjust the pressure operated mechanism.

11. In a device of the character described, the combination of a plurality of distributing pipes, valves to normally close the latter, a spindle proximate the valves, cams on the spindle in different relative positions, a suction main, a cylinder in the latter, a piston in the cylinder, and means connecting the piston and spindle.

12. In a device of the character described, the combination with a casing, a plurality of distributing pipes communicating therewith, and independent valves adapted to

close the pipes, guides on the valves, springs in the guides to normally seat the valves, a spindle rotatably mounted in the casing, cams on the spindle adapted to engage the guides, a suction main, a cylinder in the latter, a piston in the cylinder and mechanism operated by the cylinder to longitudinally move the spindle.

In testimony whereof I affix my signature to this specification in the presence of two witnesses.

WILHELM WOLF.
